COMMUNION CUP TRAY

Gordon R. Davis, 8729 Orion Circle,
El Paso, Tex. 79904

Filed Jan. 2, 1974, Ser. No. 429,716

Term of patent 14 years

Int. Cl. D7—01

U.S. Cl. D7—17

Fig. 1

Fig. 2

Fig. 3

Fig. 4

FIG. 1 is a top perspective view of a communion cup tray showing my new design;

FIG. 2 is a bottom perspective view thereof;

FIG. 3 is a top plan view thereof with the cover removed for convenience of illustration; and

FIG. 4 is a side elevational view thereof partially in section.

I claim:

The ornamental design for a communion cup tray, substantially as shown and described.
